CARPET SWEEPER

Paul J. Daniels, Milwaukee, Wis.

Application July 28, 1943, Serial No. 496,453

8 Claims. (Cl. 15—48)

This invention relates to improvements in carpet sweepers.

Heretofore carpet sweepers have been constructed with bottom dust-collecting pans which are movable to an open position when it is desired to empty the sweeper. Due to this arrangement there is necessarily an imperfect seal around the edges of the bottom pans which results in a leakage of dust while cleaning or while moving the carpet sweeper from one room to another. In addition these sweepers are usually provided with emptying mechanism including pan axles, springs and levers. This mechanism is necessarily subject to wear, as a result of continuous use, usually necessitating repair from time to time. Furthermore, the pivoted pans and connected mechanism become loose in time and cause a rattling or similar noise when the sweeper is being used.

It is a general object of the present invention to provide an improved carpet sweeper, in which the case may be formed either of wood or metal, embodying a fixed, solid pan construction together with novel means, independent of the pans, for discharging the dirt when it is desired to clean the sweeper. In the improved construction the edges of the pans are sealed in such a manner as to positively prevent the escape of dust from the bottom of the sweeper. In addition, the cover of the sweeper is formed with one or more doors through which dust may be discharged when the sweeper is inverted, and when the bail is parallel to the sweeper bottom.

A further object of the invention is to provide an improved carpet sweeper having a case construction which renders the manufacture of the sweeper relatively inexpensive and which greatly simplifies the assembly operations, the number of parts being substantially reduced over sweepers now on the market.

While the present invention is applicable to sweepers in which the case is formed of either wood or metal, the construction, nevertheless, lends itself particularly well to the formation of a metal case formed principally of two blanks. One of these blanks includes the top of the case and the end bells, and the other blank forms the two pans together with the end bulkheads. In this construction all necessary holes, bulbs, drawings, upsets, and other shapes may be formed in the blanking operation, so that the attachment of the wheel, bail and brush assemblies is rendered very simple.

A more specific object of the invention is to provide a carpet sweeper, as above described, where-

in the top of the case is formed with one or more doors. These doors are positioned above the pans and are preferably, but not necessarily, hinged. When the sweeper is in a normal position of use these doors blend into the lines of the top of the sweeper to provide a neat and attractive appearance. On the other hand when the doors are open, and when the sweeper is inverted, the doors permit a discharge of dirt from the sweeper pans.

10 A further, more specific object of the invention is to provide a construction as above described wherein the hinged doors may be equipped with flaps which project inwardly beyond the hinges. These flaps are so arranged that when the doors 15 are opened, the movable edges of the flaps engage the upper edges of the pan lips to serve as gates between the brush and back of the pan. Thus, dirt or sweepings cannot fall onto the brush during the emptying operation. A still further object of 20 the invention is to provide a construction, as above described, wherein the gate forming flaps of the doors may have their free edges in the form of combs. These combs may be positioned to engage the brush when the doors are closed and 25 when the sweeper is in use.

A further object of the invention is to provide, in the metal carpet sweeper, means on the outer shell adapted to receive the upper edges of the bulkheads to insure proper location of the pans 30 and under structure in assembly. This feature also facilitates the attachment of the bulkheads to the upper shell.

35 A further object of the invention is to provide a carpet sweeper wherein the major portion of the case may be formed of metal but wherein the side rails are preferably formed of wood or similar shock resisting material, the said side rails being 40 designed to cooperate in assembly with both the pan and cover portions and to extend past the bulkheads to support the end bells of the cover shell.

45 A further object of the invention is to provide a metal case construction wherein the major portion of the case is formed from two cooperating blanks, which construction may be used either with the improved upper door feature or in constructions wherein the top of the shell is solid.

With the above and other objects in view the invention consists of the improved carpet sweeper, 50 and all its parts and combinations, as set forth in the claims, and all equivalents thereof.

The accompanying drawings illustrate a number of the preferred embodiments of the invention in which the case is shown as formed principally of wood or of metal, it being understood

that, as to many of the features of the invention, other materials may be utilized. In these drawings, in which the same reference numerals designate the same or similar parts in all of the views:

Fig. 1 is a bottom view of that form of the invention utilizing wood for the case construction;

Fig. 2 is a longitudinal sectional view taken approximately on the line 2-2 of Fig. 1;

Fig. 3 is a transverse sectional view through the sweeper of Fig. 1 showing the sweeper inverted and in dumping position. The doors are indicated by full lines in the open position and by dot-and-dash in the closed position;

Fig. 4 is a perspective view of the form of Fig. 1 in a position of use;

Fig. 5 is a plan view of the blank for forming the pans and end bulkheads in the metal model;

Fig. 6 is a plan view of the blank for forming the top shell and end bells;

Fig. 7 is a top view of the metal carpet sweeper;

Fig. 8 is a front elevational view of the metal sweeper showing part in longitudinal vertical section;

Fig. 9 is a transverse sectional view of the metal sweeper; and

Fig. 10 is a view similar to Fig. 9 illustrating a modified arrangement for the emptying doors.

Referring first to the form of sweeper illustrated in Figs. 1 to 4 inclusive, this sweeper may be constructed principally of wood and utilizes a minimum of metal parts. This wood may be either solid or plywood. Alternatively, the parts may be formed of molded pulp, composition board, or plastic.

The end bells 15 and 16 are connected in spaced position by a top platform member 17. The assembly may be accomplished by the use of dowels 18 as shown in Fig. 2. Connected by means of dowels 19 to the lower surface of the platform member 17, are end bulkheads 20. These bulkheads are spaced inwardly from the end bells 15 and 16 to provide wheel compartments 21. The surfaces of the bulkheads 20 which face inwardly, are grooved as at 22 to receive the end edges of the pans 23 and to receive the end edges of the pan lips 24. Thus, the pans are maintained in assembled position in a very simple manner and in a manner which positively precludes the escape of dust from the end edges of the pans.

The outer longitudinal edges of the pans are received in notches 25 of the side rails 26. Nails or other fastening means 27 may secure these longitudinal edges in a dust-sealing position.

As shown in Fig. 3, the upper edges of the side rails 26 (lower edges in the position of Fig. 3) are angled as at 28 and notched as at 29. Doors 30, which are hingedly connected to the end bells 15 and 16 by means of dowels 31, are movable from the dot-and-dash line position of Fig. 3 to the full line position therein. These doors, when in closed position, rest on the upper edges of the end bulkheads 20, and the free edges of the doors engage the angled edges 28 of the side rails. The opposite edges of the doors are provided with dust-sealing tongues 32 which engage shoulders 33 on the side edges of the top platform member 17 when the doors are closed.

The shaft 34 for the brush 35 has its ends extending through cut-outs 36 in the end bulkheads. This brush shaft may be removably held in position by the inwardly extending ends 37 of a bail 38. These bail ends extend through holes

in the end bells and the bail may be yieldingly spread to release the brush if desired.

The ends of the brush shaft are equipped with rollers 39 which are frictionally engaged by the wheels 40 to provide a friction drive for the brush in the usual manner. The wheels may be yieldingly mounted in any well-known manner on spring assemblies 41 which are supported on the end bulkheads as shown in Fig. 1. These spring mountings permit the wheels to yield vertically when pressure is exerted on the sweeper during use. The wheel axles may be extended into recesses 41', the edges of which limit the yielding movement of the wheels.

The ends of the side rails 26 are suitably interlocked with the end bells as at 42 in Fig. 1. In addition the end bells are formed with outwardly projecting lower edge flanges 43 which support a surrounding bumper 44 of rubber or other similar material. The arms of the bail 38 are pivoted for movement on the outside of the end bells so that the bail may be swung into engagement with the bumper 44 and parallel to the bottom of the sweeper to support the sweeper against rotation in inverted position as in Fig. 3. When in this position, the bail is clear of the doors 30 so that the latter may be opened. Also, when the bail is parallel to the bottom of the sweeper the entire sweeper may be hung up in a closet parallel to a wall to conserve room.

Suitable means may be employed to maintain the doors 30 in closed position during normal use of the sweeper. As illustrated in Fig. 3, it is preferred to utilize a band spring 45 which is connected by screws or the like 46 to the center platform member 17. The spring is maintained in the slightly curved position of Fig. 3 by the curvature of the lower surface of the platform 17. The spring, however, tends to return to a straight line position and, therefore, when the doors 30 are closed, the ends of the spring 45 bear against the lower surfaces of the doors so that there is yielding resistance to open movement. When the doors are in the open position 45 of Fig. 3 the spring co-acts with the tongues 32 to yieldingly retain the doors in open position.

Referring now particularly to the form of the invention illustrated in Figs. 5 to 9 inclusive, the case of the invention is formed principally from the two blanks illustrated in Figs. 5 and 6. These blanks may be conveniently stamped out of sheet metal, but other suitable materials may, of course, be employed. The blank of Fig. 5 is adapted to produce the pan and bulkhead assembly. The end bulkheads 47 are integral with the end edges of the pan portions 48 and are bendable upwardly in assembly on the lines 49. The blank is cut out, as at 50, at each end to provide openings for the brush shaft and the blank interior is also cut along a longitudinal line 51. The material on each side of the cut is bent upwardly on the lines 52 to provide pan lip portions 53. In addition, the outer longitudinal edges of the pan portions 48 have flanges 54 and the curved edges of the bulkheads have flanges 55. The flanges 54 are foldable on the lines 56 and the flanges 55 are foldable on the lines 57. Tongues 58' may also be cut in the blank and these tongues may be bent outwardly 70 during assembly and secured to the pan lip portions 53 to hold the latter in assembled position, as in Fig. 9. In addition the bulkhead portions 47 may be formed with offset circular areas 59 which provide recesses on the opposite side of the blank and which perform the function of

the recesses 41' of the form of the invention shown in Fig. 2.

The other blank (see Fig. 6) includes a top portion 59 formed with a longitudinal center platform part 60 and with dust discharge openings 61 on each side of the platform 60. The end bells 62 are integral with the end edges of the top member and foldable downwardly therefrom on the line 63. The lower edges of the end bells 62 may be formed with flange portions 64 which are foldable outwardly at the time of assembly on the lines 65 to form retaining flanges for the rubber bumper 69 as shown in Fig. 8. Also, the outer longitudinal edges of the top member 59 may be formed with flanges 66 foldable on the lines 67.

In assembling the sweeper thus formed, it is desirable to utilize wooden side rails 68, as shown in Fig. 9. The outer flanges 54 of the pans 48 are bent to extend into grooves 54', as shown in Fig. 9. Thus the outer longitudinal edges of the pans are sealed against the escape of dust. The upwardly bent bulkhead portions 47 have their upper edge flanges 55 seated against shoulders 70 formed in the blank portion 59. Thus the bulkheads are retained in upright position and automatically spaced from the end bells. The flanges 55 may be secured by any desired fastening means or by welding to the underside of the top of the case. As beforementioned, the pan lip portions 53 are retained in proper assembled position by the tongues 58' and the end edges of said lips may be sealed to the bulkhead portions. As shown in Fig. 8, the wheel compartments 71 are formed between the end bell portions 62 which are integral with the top of the case and between the bulkhead portions 47 which are integral with the pan assembly. The brush member 72 is held in position by the ends of the bail 73 in the same manner as heretofore described in connection with the form of the invention of Figs. 1 and 2. The wheels 74 are also mounted in the same manner as shown and described in connection with Figs. 1 and 2 and are capable of yielding upwardly under pressure. The wheel axles may be made to extend into the recesses formed at 58 (Fig. 5) to limit the yielding movement of the wheels. This feature is also the same as heretofore described in connection with the recesses 41' of Fig. 2.

Doors 75 (see Fig. 9) are hingedly connected, as at 76, to the longitudinal edges of the center platform portion 60. These doors have flaps 77 which project into the case at an angle beyond the hinges. When the doors are in the open position, indicated by dot-and-dash lines in Fig. 9, the flaps engage the upper edges of the pan lips 53 to form a gate. Thus, when the doors are opened and when the sweeper is inverted for dumping, dirt cannot fall over the upper edges of the pan lips and onto the brush. In addition the free edges of the flaps 77 may be serrated, as at 78, or provided with comb teeth. Thus when the doors are in the closed position of Fig. 9, the comb portions engage the periphery of the bristles of the brush 72 to serve as brush combs. Any suitable means may be employed for locking the doors in closed position and, if desired, means may also be utilized for maintaining the doors in the open position during dumping.

While hinged doors are the most convenient and are, therefore, preferable, other types of movable doors may be employed. Referring to Fig. 10 the doors 75' are mounted on the outer ends of swinging arms 79. These arms swing on pivot

points 80 to permit the inner edges of the doors to swing within the case as indicated by the dot-and-dash lines in Fig. 10.

It is apparent from the above that in both forms of the invention the pan assemblies are fixed and permanently sealed against the downwardly escape of dust. It is also apparent that dumping of the sweeper can be readily accomplished by opening the doors and by inverting the sweeper. The construction is such that all pan axles, springs and levers usually employed in connection with bottom dump constructions are eliminated. This also renders the mechanism more simple to manufacture and assemble and minimizes the necessity for repairs. In addition, by eliminating the bottom door operating mechanism, the over-all height of the case is considerably lowered. Thus the sweeper may be pushed under certain types of furniture more readily. While the novel case construction has particular utility in connection with a sweeper having top discharge doors, nevertheless the arrangement is suitable for use on conventional types of sweepers. This is particularly true of the form of the invention disclosed in Figs. 5 and 6 wherein the main portions of the case including the pans, bulkheads and end bells, are formed from two flat blanks.

Various changes and modifications may be made without departing from the spirit of the invention and all of such changes are contemplated as may come within the scope of the claims.

What I claim is:

1. In a carpet sweeper case construction, a longitudinally extending top member having end bells integral therewith and projecting downwardly therefrom, there being shoulders extending transversely on the inner side of the top member near each end and spaced inwardly therefrom a one-piece pan and bulkhead assembly including transversely spaced pan portions having integral upwardly bent lips at the inner longitudinal edges of said pan portions and including bulkhead portions bent upwardly from the end edges of the pan portions, side rails connecting the end edges of the bulkheads to hold the latter in spaced position within the end bells, and means for connecting upper edge portions of the bulkheads against the transverse shoulders of the top member.

2. In a carpet sweeper case construction, a longitudinally extending top member having a longitudinal dust discharge opening on each side, said top member also having end bells integral therewith and projecting downwardly therefrom, a one-piece pan and bulkhead assembly including transversely spaced pan portions having integral upwardly bent lips at the inner longitudinal edges of said pan portions and including bulkhead portions bent upwardly from the end edges of the pan portions, side rails connecting the end edges of the bulkheads to hold the latter in spaced position within the end bells, means for effecting a dustproof connection between upper edge portions of the bulkheads and the top member, said dust discharge openings of the top member terminating at said last mentioned means, and movable doors normally closing the openings in the top member.

3. In a carpet sweeper having a case portion provided with a top dust discharge opening and having a brush, a bottom dustpan below said opening having an upturned lip extending parallel to said brush, and a hinged door normally closing said opening, said door having a flap at its

hinged edge projecting within the case and extending parallel to the pan lip, said flap being of such length as to engage said lip when the door is open to prevent dirt from falling on the brush when said dirt is being emptied from the top opening while the sweeper is inverted.

4. In a carpet sweeper having a case portion provided with a top dust discharge opening and having a brush, a bottom dustpan below said opening having an upturned lip extending parallel to said brush, and a hinged door normally closing said opening, said door having a flap at its hinged edge projecting within the case and extending parallel to the pan lip, said flap being of such length as to engage said lip when the door is open to prevent dirt from falling on the brush when said dirt is being emptied from the top opening while the sweeper is inverted and said flap having its free edge in the form of a comb which engages the brush when the door is closed.

5. In a carpet sweeper case construction, a longitudinally extending top member having a longitudinal dust discharge opening on each side, said top member also having end bells integral therewith and projecting downwardly therefrom, a one-piece pan and bulkhead assembly including transversely spaced pan portions and including bulkhead portions bent upwardly from the end edges of the pan portions, said bulkhead portions being spaced from the end bells to provide wheel compartments therebetween, side rails connecting the end edges of the bulkheads, means for connecting the pan and bulkhead assembly to the top member, and movable doors normally closing the openings in the top member, the ends of said doors and openings terminating adjacent the upper edges of the bulkheads so that the tops of the wheel compartments remain closed when the doors are open.

6. In a carpet sweeper case construction having a top member formed of material which may be shaped in a press or mold and provided with in-

tegral end bells projecting downwardly therefrom, said top member being formed with transversely extending offsets near each end and spaced inwardly therefrom to provide internal shoulders, a one-piece pan and bulkhead assembly formed of like material and including transversely spaced pan portions and including bulkhead portions bent upwardly from the end edges of the pan portions, side rails of wood or the like connected to the end edges of the bulkheads to hold the latter in spaced position from the end bells, and means for connecting the pan and bulkhead assembly to the top member, upper edge portions of the bulkheads engaging the transverse shoulders of the top member.

7. In a carpet sweeper having a case portion provided with a top dust discharge opening and having a brush, a bottom dustpan below said opening having an upturned lip extending parallel to said brush, and a hinged door normally closing said opening, said door having a flap at its hinged edge projecting within the case and extending parallel to the pan lip, said flap being of such length as to cooperate with said lip when the door is open to direct dirt away from the brush when said dirt is being emptied from the top opening while the sweeper is inverted.

8. In a carpet sweeper having a case portion provided with a top dust discharge opening and having a brush, a bottom dustpan below said opening having an upturned lip extending parallel to said brush, and a hinged door normally closing said opening, said door having a flap at its hinged edge projecting within the case and extending parallel to the pan lip, said flap being of such length as to cooperate with said lip when the door is open to direct dirt away from the brush when said dirt is being emptied from the top opening while the sweeper is inverted and said flap having its free edge in the form of a comb which engages the brush when the door is closed.

PAUL J. DANIELS.
